UNITED STATES PATENT OFFICE

LESTER S. SEELIG, OF NEW ORLEANS, LOUISIANA

DESIGN FOR A LAMP SHADE

Application filed May 22, 1931. Serial No. 39,933. Term of patent 7 years.

To all whom it may concern:

Be it known that I, LESTER S. SEELIG, a citizen of the United States of America, residing at New Orleans, parish of Orleans, State of Louisiana, have invented a new, original, and ornamental Design for a Lamp Shade, of which the following is a specification, reference being had to the accompanying drawings, forming a part thereof.

Figure 1 is a plan view, and

Figure 2 is a perspective view showing my new design.

I claim:

The ornamental design for a lamp shade as shown.

LESTER S. SEELIG.
